LOAD DISCHARGING CAR

Argyle Campbell, Chicago, Ill., assignor to Enterprise Railway Equipment Company, Chicago, Ill., a corporation of Illinois

Application June 23, 1933, Serial No. 677,231

10 Claims. (Cl. 105—282)

My invention relates to improvements in load discharging cars.

An object of my invention is to provide an improved load discharging car of a type requiring tightly fitting doors for the hauling of bulk material such as cement, which under certain conditions is free running and under other conditions will arch and pack very tightly above the discharge openings and can only be discharged through bottom outlets after the arch has been ruptured.

An object of my invention is to provide an improved sliding door and door operating means whereby the doors may be conveniently operated and controlled from the side of the car.

Still another object of my invention resides in the arrangement of hoppers and sloping floor sheets in relation to discharge outlets whereby the flow of material through the outlets may be controlled and the possibility of the material arching in the hoppers reduced to a minimum.

My invention also resides in certain other features and details of construction such as will be more fully pointed out hereinafter and claimed.

Further objects of my invention will appear from the drawings appended hereto, wherein:

Fig. 1 is a side elevational view of a hopper car embodying my improved construction;

Fig. 2 is a top plan view of the car illustrated in Fig. 1, certain parts of the car being shown in section to more fully illustrate the construction;

Fig. 3 is a fractional view on an enlarged scale taken through the lower portion of one of the hoppers on a line 3—3 of Fig. 2;

Fig. 4 is a fractional view on an enlarged scale of a portion of Fig. 1 showing the lower portion of one of the hoppers together with certain related car construction;

Fig. 5 is an end view of the lower portion of one of the hoppers as viewed on a line 5—5 of Fig. 3;

Fig. 6 is a fractional view of a portion of a hopper adjacent the door operating and locking means as viewed on a line 6—6 of Fig. 5; and

Fig. 7 is a transverse vertical sectional view taken through the lower portion of the car and on a line 7—7 of Fig. 3.

Referring now to the drawings wherein my improved construction is shown as applied to a hopper dump car, A indicates the track upon which the car is adapted to move; B the trucks at each end of the car, and the body of the car at C.

The trucks B at the respective ends of the car are illustrated by the wheels indicated at 10.

According to the present embodiment of the invention, my improved construction is shown as

applied to a car having longitudinal centersills 11 extending lengthwise through the car, said centersills consisting of a pair of channel shaped members 12, each having a vertical web wall section 13 and inwardly directed upper and lower flanges 14. The centersill is surmounted by an inverted V-shaped ridge 15 which extends lengthwise through the car and divides the car to form transversely aligned hoppers on each side of the centersill, as indicated at 16—16, as hereinafter described.

The vertical side walls of the car are indicated at 17, and sloping end walls 18 are provided at each end of the car, said last named walls sloping downwardly at a steep angle above the trucks 15 of the car.

The upper part of the car is provided with a suitable roof 19. Intermediate the sloping ends 18 the car is divided transversely by two partitions 119—119 extending preferably intermediate the respective side walls from the bottom of the centersills to the top of the car and forming supports for the roof 19. The partitions 119 provide two large end bins and an intermediate bin of smaller proportions. Access is provided to the interior of these bins by a series of trap doors 20 disposed in the roof of the car and spaced on opposite sides of the longitudinal center to provide four doors for each of the end bins and two doors for the intermediate bins.

The transverse web sections 119 are suitably coped as indicated at 21 (Fig. 7) to straddle the centersill, and on each side of the centersills the web plates are extended downwardly to the lower plane of the centersill 12. The lower margins of the said webs are reinforced by transversely extending angles 22 and the sections on the opposite side of the centersills are united by a transversely extended lower cover plate 23.

Referring now to the hoppers 16 of which there are six per car in the particular embodiment shown: These are arranged in transverse aligned pairs on the opposite sides of the centersills; but inasmuch as the construction is identical for the various hoppers, the description hereinafter will be confined to only one of said hoppers.

The said hopper 16 includes an inner vertical wall 24 which constitutes a downwardly extension of the centersill web 13. The outer side of the hopper includes a downwardly sloping plate 25 (Fig. 7) which extends from the lower portion of the car side wall 17 to a location substantially in alignment with the lower portion of wall 24 and which is spaced therefrom transversely of the car for a distance sufficient to pro-

vide a discharge opening. Sloping lengthwise of the car from each transverse partition sheet 119 and riveted thereto are sloping hopper plates 26 which slope longitudinally of the car and meet 5 with plates 24 and 25 to form the lower parts of the hopper section. At the ends of the car the sloping floors 18 form one wall of the end hoppers and are extended to the same level as the lower marginal edges of walls 24 and 25.

10 At the lower portion of each hopper 16 there is provided a frame D which is formed with an upwardly extending wall 27 which overlies and conforms to the shape of the hopper and is riveted thereto. This frame is preferably in the 15 form of a casting, and below the attaching wall portion 27 the casting is formed on the inner sides of the walls on the opposite sides of the frame with a horizontal extending groove 28, said groove being defined by upper and lower horizontal walls 29 and 30 and a vertical wall 31. The wall 30 presents a flat surface on the inner side of each wall which constitutes supporting shelves for a sliding gate E, the latter being adapted for sliding movement lengthwise of the 20 car to control the discharge of the lading in the hopper. The gate E, which is preferably in the form of a casting, is mounted for sliding movement in the grooves 28 and extended beyond said grooves and frame to provide a portion projecting beyond one end of the frame D, there being provided a slotted opening 32 in one end of the frame through which the gate extends. The lower portion of the last named opening is in the 25 form of a flat wall 33 (Fig. 3) having a surface disposed in alignment with and forming a continuation of the lower walls 30 of the grooves 28. The opposite end of the frame casting is provided with a ledge portion 34 which also forms a continuation of surfaces 30 and 33 and thereby 30 provides a flat bearing surface extending continuously on a common level to provide a flat surface around a discharge opening of rectangular shape immediately below the sliding gate E.

The upper wall of the frame at the outer end 35 thereof and above the slot 32 is formed with an angular shaped recess 35 defined by a vertical depending flange 36 and a horizontal wall 37, said last named wall extending continuously across the frame from side to side thereof and being disposed somewhat above the lower marginal portion 40 of edge of wall 36. The recess 35 is adapted to accommodate an upstanding wall 38 formed integrally with the gate E, thereby providing that when the gate is positioned to close the discharge 45 opening, said upstanding wall 38 fits into the recess 35 and the close cooperating relation between the parts provides a sealing joint at the outer edge of the gate to prevent the entry of rain or moisture within the hopper. The gate 50 E is provided at the side edges thereof with runways 39 which fit in the grooves 28, and the lower surfaces of said runways are disposed in alignment with a surface 40 extending from side to side of the door at the inner edge thereof. The 55 upper surface of the gate presents a flat surface and at its outer edge is beveled downwardly as indicated at 41 for the purpose of displacing any material which might lodge on the supporting ledges and normally interfere with the free operation of the door.

The beveled edge 41 is at all times in contact with the load and as the gate approaches the closed position, the edge of the door eases the material upwardly along the sloping floor 18 of the hopper end wall. It will be noted that the

ends of the grooves 28 are sloped to correspond with the sloping floor 18 and thus, with the gate in closed position the angle made between the beveled end of the gate and the sloping floor is slightly in excess of 90 degrees, thus providing for easement of the material in advance of the gate and preventing undue packing of the lading at the ends of the slots or under the gate.

The gate on the underside intermediate the runways 39 is provided with a series of teeth 42 which preferably extend continuously from side to side of the gate and form a series of reinforcements for the gate. The teeth 42 are adapted to mesh with pinions 43-43 carried on a shaft 44 extending from side to side of the frame casting and rotatably mounted in bearings 45-45. The bearings 45 are disposed at the sides of the frame casting and preferably formed integrally with walls 46-46, the latter in turn being formed integrally with the frame. The walls 46 overhang the frame proper and constitute means for supporting a pair of supplementary guiding rails 47-47, the latter extending beyond the frame casting and beneath the ridge sheets 26 for supporting the gate E in its open or partially open position.

The guiding rails 47 are each formed of two angle shaped members 48 and 49 riveted together or otherwise suitably united to provide two horizontal guide walls indicated at 50 and 51 respectively. Said guide walls are arranged to form grooves presenting continuations of grooves 28. The angles 48 are riveted directly to the walls 46 by means of rivets 52 and the angle 49 is riveted to the angle 48 independently of and beyond the integral walls 46. The said guide rails 47, as will be understood, are spaced transversely of the car a distance corresponding to the width of the sliding gate, and the respective guide rail means on the opposite sides of the hopper are united by a flat strap 53 which in addition to forming a tie for the rails also constitutes a stop for limiting the opening movement of the sliding gate.

The operating shaft 44 is extended beyond the outer wall 46 of the frame and is provided with a suitable socket 54 (Fig. 5) formed with a plurality of openings 55 for the reception of a removable bar, whereby rotation of the shaft is effected and the gate moved. The openings 55 are preferably disposed at an angle corresponding substantially to the slope of the outer wall 25 of the hopper, thereby permitting the insertion of the bar in such a manner and at an angle to clear the sloping side walls and permit the bar to extend beyond the car sides. For retaining the closure gate in its closed position, I provide a pivotal locking dog 56 which is pivoted at 57 on a lug 58 disposed above the sliding gate, the pivotal axis of the dog extending at right angles to the plane of movement of the gate. The lug 58 is preferably formed integrally with an upper extension 59 of wall 46 and on the inner side thereof. The dog is provided with a projection 60 which extends outwardly beyond the wall 59 thereby providing convenient means for rotating the dog. Said dog is provided with an arcuate face 61 adapted to register with a correspondingly formed seat 62 on the gate. The parts when in closed position are best indicated in Fig. 6.

For the purpose of further assuring maintenance of the locking dog in operative position and providing convenient means for receiving a car seal, there is provided a sealing pin 63 extending through an opening in wall 46 and 75

through an inwardly spaced wall 64 in the form of a key slot and the outer end of sealing pin 63 is formed likewise and has a slot 65 therein for the reception of a car seal. The slot 65 of the pin 63 is adapted to lie against an integral wall 66 when the gate is closed and the pin in operative position, said integral wall 66 having a slot 67 therein adapted to register in alignment with the slot 65 of pin 63 thereby permitting of placing a sealing strip through both members.

Below the gate the sloping walls of the frame are extended downwardly as indicated at 68 for an appreciable distance to present a funnel shaped discharge chute which terminates in a discharge outlet 69 disposed below the pinions 43. Around the outlet 69 there is disposed an outstanding ledge 70 which extends completely around the discharge outlet, and below said ledge on two sides of the opening there is a groove 71, said groove 71 being used for the purpose of accommodating the frame of a removable discharge chute which is positioned in the two sides of the groove and bolted or clipped to the ledge 70 at the other two sides of the discharge opening. The arrangement of the grooves is such as to present the open end of the groove towards the wheels and the outer side of the track thereby facilitating the positioning of the removable chute, said edge 70 forms a continuous flat abutment against which the top of the removable chute is adapted to bear when in position.

The arrangement and construction of the hoppers is such as to minimize the packing of the material in the bins above the outlet openings, due to arching. One of the difficulties encountered in connection with the handling of bulk cement and similar material is due to the fact that the material flows very freely when first loaded and therefore provision has to be made for prevention of leakage and for restricting the flow in the desired quantities. On the other hand, when the material has been hauled over a long distance there is a tendency for the lading to arch and pack in the bins, thereby necessitating the use of large openings and the application of external force to initiate the free flow of the material. The use of large discharge outlets, however, is not conducive to a proper control of the material as it issues from the outlets, and I have therefore embodied in my construction features in the construction of the hoppers and door openings which are such as to provide the restricted outlets where free flow of material is desired and also minimize the liability for the material to arch in the hoppers above the openings. It will be noted that in my construction I retain a discharge outlet of standard dimension having a comparatively small area and dispose the control gate on a higher plane and at a location where the opening is of such increased size to break the arch, as it will be appreciated that once the arch has been broken, free flow of the material commences and the only factor then to be taken into consideration is the proper regulation and restriction of the flow of material.

The arrangement of the hoppers lengthwise of the car, separated by intervening ridge shaped stationary floors, provides a construction having ample space in which to locate the guide rails and permit of the discharge gates assuming a position beneath the stationary floor when moved to open position.

The operation of the device is as follows: As-

suming the parts to be positioned as in Fig. 6, the sealing pin 63 is rotated until such time as the flat portion thereof registers with the slot in the wall 46 when the pin is moved lengthwise in its bearing until such time as it is clear of the locking dog 56, after which the locking dog is rotated and moved to an over-balanced position as indicated in conventional dotted lines in Fig. 6, and a bar is then inserted in one of the openings 55 of the operating socket 54 and the bar rotated in a clockwise direction thereby rotating the pinions 43 and causing the gate E to move along the slotted guide rails provided.

I claim:

1. In a railway car, the combination with a discharging hopper; of a sliding gate at the lower portion adapted to close the opening, means for preventing lengthwise movement of said gate when in closed position, said means including a pivotally mounted element pivoted on an axis disposed at right angles to the plane of movement of the gate and having a portion adapted to be swung into the path of movement of the gate; and a lock and sealing means for locking said pivotally mounted element in operative position, said means including a pin having lengthwise movement parallel with the axis of the pivoted element and extending through the said element and through an adjacent portion of the car structure.

2. In a railway car, the combination with a discharge hopper; of a frame at the lower portion of the hopper; a sliding gate mounted in said frame and said frame having a discharge outlet; supporting horizontal walls on the inner side of the frame for supporting the sliding gate; vertical wall means formed integral with the said frame on either side of the sliding gate; supplementary guiding and supporting walls attached to said frame for supporting the gate when in open position; rack means on the underside of the gate; rotatably mounted pinions for moving the rack means; and a pivotally mounted element pivoted above the plane of the gate to swing on an axis substantially parallel with the axis of the pinions, said element being adapted to have a portion moved in the path of movement of the gate for retaining said gate in closed position.

3. As an article of manufacture, a frame adapted to form the lower portion of a discharge opening and presenting in a self-contained unit; a funnel shape frame presenting flanges on four sides for attachment to the hopper sheets of a discharge hopper, and terminating in a discharge outlet, said frame having therein runways for a sliding closure including a rack; means for moving the closure and pinions operating the rack of the closure; an operating shaft for rotating the pinions; bearings for the shaft; pivotal locking member adjacent the outer edge of the closure adapted to move in the path of the closure when the latter is in closed position; and a slotted pin adapted to extend through the frame and through a portion of the locking member, said pin and the framework having aligned apertures adapted to receive a car seal.

4. In a hopper car, a discharge outlet including a four-sided frame having in one of the walls thereof a slotted opening; and a sliding gate adapted to extend through the said opening for movement therein, said frame and gate on the outer sides thereof of adjacent above the slot being provided with cooperating overlapping surfaces to form a sealing means, said gate on its underside having rack teeth extending from side to side thereof and forming strengthening ribs for

the gate and sealing means beneath the gate for the slotted opening, said sealing means including a ledge extending in the direction of movement of the door a sufficient distance to extend beneath 5 and overlap a plurality of the teeth of the rack.

5. In a railway car adapted for handling bulk cement and the like, the combination of a hopper and an outlet casting positioned at the lower portion of the hopper, a sliding gate disposed in the 10 outlet casting, said gate and casting having cooperating bearing surfaces for supporting the gate, said gate being of appreciable thickness and formed on its underside with a series of rack teeth extending transversely to the direction of movement 15 of the door, said sliding gate having one end thereof projecting outwardly beyond the outlet casting and having the opposite end beveled downwardly in the direction of the flow of material from the hopper, the bevel being exposed 20 to the lading and acting to divert the material upwardly as the gate is moved to closed position.

6. In a railway car having a discharge outlet, the combination of a sliding gate adapted to close the outlet, means for moving the sliding gate including 25 rack means formed on the underside of the gate and rotatable pinion means for cooperation with the rack for moving the gate, and means for locking the gate in operative position, including a locking element mounted on 30 an axis substantially parallel with the axis of the pinion means, said element being adapted to have a portion thereof movable to a position in the path of movement of the sliding gate.

7. In a railway car having a discharge outlet, 35 the combination of a siding gate adapted to close the outlet, supporting means for the sliding gate including inwardly projecting shelf means formed adjacent the discharge outlet, means for moving the sliding gate along the shelf including rack 40 means formed on the underside of the gate and rotatable pinion means cooperating with said rack means, and means for locking the gate in operative position including a locking element mounted on an axis lying substantially parallel 45 with the axis of the pinion means, said locking element having an arcuate portion adapted to register with an abutment formed on the gate.

8. As an article of manufacture, a frame 50 adapted to form the lower portion of a discharge hopper and presenting in a self-contained unit a funnel-shaped frame having flanges for attachment to the hopper and having its lower margin terminating in a discharge outlet, a sliding closure for the discharge outlet, runways on 55 the frame affording supporting means for the sliding closure, rack means on the underside of

the sliding closure extended substantially from side to side of the closure, pinions for cooperating with the rack of the closure, an operating shaft for rotating the pinions, bearings for rotatably supporting the shaft, and means on the 5 end of the shaft for rotating the shaft, said last named means including a member rigidly united with the shaft and having a plurality of socket openings lying at an obtuse angle with the axis of the shaft and thereby permitting the insertion of 10 an operating bar at an obtuse angle to the axis of the shaft.

9. In a railway car, the combination with a hopper defined in part by sloping walls, an outlet casting positioned at the lower portion of the 15 hopper having walls overlying the walls of the hopper and secured thereto, a sliding gate disposed in the frame and adapted to close the outlet, said sliding gate having rack means on the underside thereof, rotatably mounted pinions 20 cooperating with the rack means for moving the sliding gate, a shaft rotatably mounted in the outlet casting for rotating the pinions, said shaft having one end extending outwardly beyond the outlet casting and formed with a projecting portion 25 extending beneath one of the sloping walls of the hopper, a member rigidly mounted on the projecting portion of the shaft and having openings therein corresponding substantially to the slope of the outlet walls of the hopper thereby 30 permitting the insertion of a removable operating bar therein at an angle corresponding to the sloping side wall of the hopper.

10. In a hopper car the combination with a discharge hopper having inclined walls terminating in an opening at the bottom, a slideable gate member for controlling the opening, a frame for supporting said gate, comprising a casting surrounding said opening and having inclined walls 40 secured to the walls of the hopper and terminating below the gate to form an outlet of lesser dimensions than said opening, said casting having a slot through one of its end walls through which said gate is adapted to slide and having on its opposite end wall a ledge upon which the forward 45 edge of the gate is supported in closed position, said frame casting also having in its two side walls, guide channels for guiding the side edges of the gate, said gate having its forward edge beveled at an appreciable angle in the direction of flow of 50 the lading to divert upwardly any material resting in said guide channels or upon said ledge as the gate is moved to closed position to relieve the gate of interference during its movement.

55 ARGYLE CAMPBELL.
